(57) **CLAIM**

The ornamental design for a tire, as shown and described.

DESCRIPTION

FIG. 1 is a front perspective view of a tire according to the new design;

FIG. 2 is a front elevation view thereof; and,

FIG. 3 is a partial front perspective view thereof.

The broken lines depict environmental subject matter only; broken line features and any surfaces of the design not shown, including interior surfaces, form no part of the claimed design.
